UNITED STATES PATENT OFFICE.

LOUIS C. HAMEL, OF APPLETON, WISCONSIN.

SIGN.

No. 813,554.

Specification of Letters Patent.

Patented Feb. 27, 1906.

Application filed September 6, 1905. Serial No. 277,234.

To all whom it may concern:

Be it known that I, LOUIS C. HAMEL, a citizen of the United States, residing at Appleton, in the county of Outagamie and State 5 of Wisconsin, have invented a new and useful Sign, of which the following is a specification.

This invention relates to signs, and has for its object to provide a device of the class embodying new and improved features of simplicity, utility, durability, and sightliness.

A further object of the invention is to provide a column with outstanding parallel arms and improved characters for association with 15 the arms.

A further object of the invention is to provide a hollow column with arms inserted therethrough and extending upon opposite sides and improved means for holding the 20 arms in position.

Specifically, the object of the invention is to provide a hollow column with aligned openings transecting the sides and with a hollow or cylindrical member within the column 25 with openings registering with the openings in the column and through which extend the arms. Pressure is exerted on the inner member by the ornamental head to force it down upon and to hold the arms. Characters are 30 formed of sheet or other form of metal slitted at each end and the tongues bent out each way to embrace the arms.

With these and other objects in view the present invention consists in the combination 35 and arrangement of parts, as will be herein-after fully described, shown in the accompanying drawings, and particularly pointed out in the appended claims, it being understood that such changes in the form, proportion, size, and minor details may be made as 40 fall within the scope of the claims.

In the drawings, Figure 1 is a view of the improved sign-post in side elevation. Fig. 2 is a vertical longitudinal detail sectional view. 45 Fig. 3 is a transverse sectional view on line 3 of Fig. 1. Fig. 4 is a transverse sectional view of a modified form. Fig. 5 is a detail side elevation of one of the characters for use in association with the column and arms.

50 Like characters of reference indicate corresponding parts in all of the figures of the drawings.

In its preferred embodiment the improved sign forming the subject-matter of this application comprises a tubular column 10 of any required height and with any approved means

for securing in the ground, as the base-point 11. The column is provided with any approved number of spaced openings 12, piercing the column at diametrically opposite 60 points. Within the tubular column 10 is disposed a tube or cylinder 13, provided with openings 14, registering with the openings 12 in the column. Through the registering openings 12 and 14 are inserted any approved 65 number of arms 15, extending upon opposite sides of the column to the required distance. To bind the arms firmly in position, a head 16 is screwed upon the upper end of the column 10 and bears against the top of the binding 70 member 13 and forces it down upon and to bind the arms. Between the parallel arms 15 are mounted the characters 17, formed of sheet or other material slitted at the upper and lower ends, as at 18, to form the lips 19. 75 The lips 19 are bent alternately and laterally in opposite directions and with the extremities again bent to planes parallel with the plane of the character and to embrace the arm, as shown in Figs. 3 and 4. When it is 80 desirable to read the sign from both sides, the arms may be in channel form, as at 20, with two rows of characters embracing the edges of the flanges 21 and with a sheet 22 of differently-colored material disposed between the 85 characters. At the ends of the arms an index character 23 will be inserted with lips similar to the lips 19, but will be secured from displacement and to bind the other characters by bolts 24.

In assembling the improved sign the column is first set where required, and the arms inserted through the openings 12 and 14. The required characters for one side are then inserted between the arms and the final index character secured in place. The connected arms are then slidably moved through the column to take up all space and the head 16 screwed on to force the binding member 13 to engage the arms. Characters are then filled 90 into the opposite side and the arms cut off at the required length and the index applied.

It is obvious that any desired number of arms may be used and extended in as many directions as found desirable. It will also be 105 noted that when two or more series of characters are to appear upon the same side of the column the lower edge of the arm above serves to engage the upper ends of the additional characters, thereby rendering it necessary to add but one arm for each additional 110 series of characters.

It will be observed that structurally the sign as herein illustrated is adapted for use as a highway-guide post for which purpose it is primarily intended, but may with equally satisfactory results be used for advertising and other purposes.

Having thus described the invention, what is claimed is—

1. In a sign, a hollow column, arms extending through and outstanding perpendicular to the column, and means internally of the column for securing the arms against displacement.
2. In a sign, a hollow column, arms extending through and outstanding from the column, and means within and longitudinally movable relative to the column for securing the arms against displacement.
3. In a sign, a hollow column, arms inserted through and extending upon opposite sides of the column, and means within the column to prevent displacement of the arms.
4. In a sign, a hollow column, arms inserted through and extending upon opposite sides of the column, binding means within the column and in engagement with the arms, and means for exerting pressure upon the binding means.
5. In a sign, a hollow column, arms inserted through and extending upon opposite sides of the column, binding means mounted and longitudinally movable within the column and in engagement with the arms, and means external of the column for exerting a pressure upon the binding means.
- 35 6. In a sign, a hollow column having open-

ings formed therethrough, a binding member within the column and having openings registering with the openings in the column, arms inserted through the openings and means for exerting a pressure upon the upper end of the binding member.

7. In a sign, a hollow column having openings formed therethrough, a cylindrical binding member mounted and longitudinally movable within the column and having openings registering with the openings in the column, arms inserted through the openings and means for exerting pressure upon the upper end of the binding member.

8. The combination with a column having outstanding parallel arms of characters composed of sheet material and having opposite ends slitted and the lips so formed bent to opposite sides to embrace the arms.

9. The combination with a hollow column having parallel arms inserted and longitudinally movable therethrough of characters composed of sheet material equal in height to the distance between the arms and having lips upon the top and bottom formed by slits and bending the lips laterally alternately in opposite directions and terminating in portions parallel with the characters and spaced apart and embracing one edge of each arm.

In testimony that I claim the foregoing as my own I have hereto affixed my signature in the presence of two witnesses.

LOUIS C. HAMEL.
